UNITED STATES PATENT OFFICE

150,407

DESIGN FOR A CANDLE

Ann Donahue, New York, N. Y., assignor to The
W. & F. Manufacturing Co., Inc., Buffalo, N. Y.

Application February 21, 1947, Serial No. 137,083

Term of patent 7 years

(Cl. D73—1)

To all whom it may concern:

Be it known that I, Ann Donahue, a citizen of the United States, residing at New York city, county of New York, State of New York, have invented a new, original, and ornamental Design for Candles, of which the following is a specification, reference being had to the accompanying drawings, forming a part thereof.

In the accompanying drawings:

Fig. 1 is a front elevation of a candle embodying my invention;

Fig. 2 is a rear elevation of the same;

Fig. 3 is one side elevation of the same;

Fig. 4 is the other side elevation of the same; and

Fig. 5 is a plan of the same.

I claim:

The ornamental design for a candle, substantially as shown.

ANN DONAHUE.
